ASH CAN AND SIEVE

Sarah McV. Meye, Jeannette, Pa.

Application June 21, 1940, Serial No. 341,767

5 Claims. (Cl. 209—249)

The invention relates to an ash can and more especially to a combined ash can and rotary sieve or sifter.

The primary object of the invention is the provision of a can of this character wherein the mouth portion thereof accommodates therein a removable sieve or sifter having a rotary agitator therein so that the loose ashes can be dropped into the can while the unspent, solid fuel can be recovered for the burning thereof within a furnace or the like, the sieve or sifter being of a novel construction and when fitted within the can will be confined by a lid or cover telescopically fitted onto the said can to avoid the escape of dust, dirt or the like to the atmosphere when operating the sieve.

Another object of the invention is the provision of a can of this character wherein the sieve or sifter is readily removable from its fitting with the can so that ashes or other substances can be sifted either within or without the can and when being sifted in the open the sieve will be conveniently supported upon the ground or a foundation.

A further object of the invention is the provision of a can of this character wherein the construction thereof and that of the sieve is novel and both interfitted with each other in a unique manner, the can or the sieve being susceptible of convenient dumping independent of each other and both the sieve and the can when separated or together may be conveniently transported.

A still further object of the invention is the provision of a can of this character, which is simple in its construction, thoroughly reliable and efficient in operation, unique in the setup of the same, susceptible of easy handling, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention and pointed out in the claims hereunto appended.

In the accompanying drawing:

Figure 1 is a vertical sectional view through a can and its sieve constructed in accordance with the invention.

Figure 2 is a fragmentary side elevation partly broken away.

Figure 3 is a top plan view with the cover or lid removed from the can.

Figure 4 is a fragmentary sectional view taken on the line 4—4 of Figure 1.

Figure 5 is a detail fragmentary side elevation of the sieve removed from the can.

Similar reference characters indicate corresponding parts throughout the several views in the drawing.

Referring to the drawing in detail, the invention comprises a can body 10, preferably made from sheet metal having a permanently closed bottom 11 and a slightly contracted neck 12 at its upper portion terminating in a mouth of substantially equilateral square formation having the rounded corners 13. The mouth is formed with a reinforcing bead 14 continuously about the same.

At diametrically opposite points in the mouth are vertical notches or slots 15 which are horizontally aligned with each other and open upwardly through the said mouth for accommodating stud bearings 16, which are built upon a solid, cylindrical body portion 17 of a wire mesh sifter or sieve, the screening or sifting fabric of which is denoted at 18. The fabric 18 is riveted or otherwise fastened marginally at the lower edge of the body 17 circumferentially thereof. The body 17 is formed with an upper outturned rim flange 19 adapted to rest upon or contact with the mouth 13 at the bead edge 14 thereof and in this manner augmented by the engagement of the bearings 16 in the notches or slots 15 the sifter or sieve will be suspended within the can 10. The sifter or sieve 18 with the body 17 thereof is readily removable from the can and for such purpose there is provided at the rim flange 19 at opposite points thereof upstanding loop handles 20.

The sifter or sieve 18 throughout the wire mesh fabric thereof is of half cylindrical contour and fitted at opposite points of the body 17 are props 21 which permit of the sifter or sieve being supported at rest upon the ground or foundation on removal thereof from the can without toppling over or side tilting. These props 21 are disposed at the opposite curved sides of the fabric 18 creating the sieve or sifter to hold the latter in an upright position when at rest without the can.

Arranged within the sieve or sifter is a rotary agitator 22 in the form of an open frame provided with stud axles 23 and 24, respectively, journaled in the bearings 16, the axle 24 being equipped with a crank handle 25 for manual turning of the agitator 22 within the sifter or sieve. The handle 25 is extended without the can 10 when the sieve or sifter is fitted within the latter.

The rim flange 19 of the body 17 is formed with a marginal reinforcing bead 26 and adapted to be

brought to rest upon the latter is a lid or cover 21 formed with an outstruck or outwardly flared annular rim 28 creating a rest shoulder 29 for contact with a bead 26 when the lid or cover 21 is placed in position for concealing the sieve or sifter and closing the can 10. This rim 28 outstruck from the lid or cover 21 enables the convenient gripping thereof at any point circumferentially of the can so that such lid or cover 21 can be conveniently removed while rising from the top or crown of the lid or cover 21 is a loop handle 29 permitting of the carrying of the lid or cover by hand.

The can 10 at opposite points thereof exteriorly of the same has fitted thereto swinging 15 grips or handles 30 facilitating the carrying of the can by hand or for the dumping of the contents therefrom.

When the lid or cover 21 is removed from at rest upon the bead 26 of the rim flange 19, the 20 sieve or sifter is readily accessible and the latter can be conveniently separated from the can 10 although it is not required that the lid or cover 21 be removed for this purpose because the sifter or sieve with the cover or lid thereon can be readily taken from the can 10 if found desirable. However, by first removing the lid or cover 21 and thereafter the sieve or sifter from the can and the placement thereof upon the ground or foundation the said lid or cover 30 can be replaced thereon so as to avoid the scattering of dust or dirt when sifting material outside of the can 10.

When the sieve or sifter is fitted within the can and the cover or lid 21 thereon, dust or 35 dirt during the sifting operation will not escape from the can 10 but will be retained therein.

In the use of the can with the sifter or sieve, the hard or solid particles of ashes are deposited within the can, both the sieve or sifter and the can being readily dumped for removing their contents. The recovered hard particles of fuel 40 can be fed into a furnace or the like for the burning thereof.

What is claimed is:

1. An article of the kind described comprising a receptacle having an open mouth at its upper end provided with opposed notches, a sieve having a rim provided with opposed bearings, the latter being releasably accommodated in said notches, an agitator operating within the sieve and journaled in said bearings, means for imparting motion to said agitator, and a cover for the said sieve and telescoped over the mouth end of said receptacle.

2. An article of the kind described comprising a receptacle having an open mouth at its upper end provided with opposed notches, a sieve having a rim provided with opposed bearings, the latter being releasably accommodated in said 60

notches, an agitator operating within the sieve and journaled in said bearings, means for imparting motion to said agitator, a cover for the said sieve and telescoped over the mouth end of said receptacle, an outturned flange formed with said sieve and having contact with the mouth end of said receptacle, and an outstruck portion formed in said cover for effecting a shoulder therein adapted to be brought to rest on said flange.

3. An article of the kind described comprising a receptacle having an open mouth at its upper end provided with opposed notches, a sieve having a rim provided with opposed bearings, the latter being releasably accommodated in said notches, an agitator operating within the sieve and journaled in said bearings, means for imparting motion to said agitator, a cover for the said sieve and telescoped over the mouth end of said receptacle, an outturned flange formed with said sieve and having contact with the mouth end of said receptacle, an outstruck portion formed in said cover for effecting a shoulder therein adapted to be brought to rest on said flange, and hand grips on said sieve at opposite points thereof.

4. An article of the kind described comprising a receptacle having an open mouth at its upper end provided with opposed notches, a sieve having a rim provided with opposed bearings, the latter being releasably accommodated in said notches, an agitator operating within the sieve and journaled in said bearings, means for imparting motion to said agitator, a cover for the said sieve and telescoped over the mouth end of said receptacle, an outturned flange formed with said sieve and having contact with the mouth end of said receptacle, an outstruck portion formed in said cover for effecting a shoulder therein adapted to be brought to rest on said flange, hand grips on said sieve at opposite points thereof, the said sieve having a semicylindrical bottom, and props arranged on the sieve diametrically opposite each other with respect to said bottom for supporting the said sieve when removed from the receptacle in an upright position while at rest upon a foundation.

5. An article of the kind described, comprising a receptacle having an open mouth at its upper end with opposed elongated notches, U-shaped supporting and reinforcing plates secured to the outer face of the receptacle around said notches, a sieve, an outwardly extending bearing carried by the sieve and entering said notches and supported by the wall of the notches and the U-shaped plates, an agitator operating within the sieve and having its shaft journaled in said bearings, and means for rotating said shaft.
